W. L. WRIGHT.
PAPER MATERIAL RECEPTACLE AND THE LIKE.
APPLICATION FILED MAR. 15, 1911.

1,107,869.

Patented Aug. 18, 1914.

UNITED STATES PATENT OFFICE.

WILBUR L. WRIGHT, OF WASHINGTON, DISTRICT OF COLUMBIA.

PAPER-MATERIAL RECEPTACLE AND THE LIKE.

1,107,869.

Specification of Letters Patent.

Patented Aug. 18, 1914.

Application filed March 15, 1911. Serial No. 614,719.

To all whom it may concern:

Be it known that I, WILBUR L. WRIGHT, a citizen of the United States, residing at Washington, District of Columbia, have invented certain new and useful Improvements in and Relating to Paper-Material Receptacles and the like; and I do hereby declare the following to be a full, clear, and exact description of the invention, such as will enable others skilled in the art to which it appertains to make and use the same.

This invention relates to certain improvements in vessels or receptacles made of paper and the like; and the objects and nature 15 of my invention will be readily understood by those skilled in the art in the light of the following explanation of the accompanying drawings illustrating what I now consider to be the preferred embodiments from among 20 other formations and arrangements within the spirit and scope of my invention.

An object of the invention is to provide certain improvements in the neck and mouth portions of bottles or receptacles made of 25 paper or equivalent material, for the purpose of greatly increasing the strength and rigidity thereof without exposing the contents of the receptacle to contact with other than the paper, or equivalent material, forming 30 the walls of the receptacle, and so as to provide the receptacle neck with a comparatively smooth interior surface without objectionable shoulders or recesses for the collection of foreign matter or the like.

35 A further object of the invention is to provide a receptacle made of paper or equivalent material with an improved stiffening neck ring and in so applying and fastening the paper material forming the bottle to 40 said ring as to cover the ring from contact with the contents of the bottle while filling and emptying, and to provide means for effectively securing or locking closures over the receptacle mouth.

45 The invention consists in certain novel features in construction and in combinations and arrangements of parts and elements as more fully and particularly set forth hereinafter.

50 Referring to the accompanying drawings;—Figure 1, is a perspective view of the mouth or neck portion of a paper receptacle formed in accordance with my invention, a closing disk provided with a pull tab or 55 handle being shown seated on the internal

seat or shoulder of the receptacle mouth to seal the same. Fig. 2, is a vertical section thereof. Fig. 3, is a vertical section through the neck portion of the receptacle and the neck ring, dotted lines indicating the form 60 of the receptacle neck when first inserted through the neck ring, full lines showing the form assumed by said neck after being spun or pressed down on the neck ring to form the receptacle mouth, the neck ring being shown dropped from proper position in said mouth, and in its original form before its outer upwardly extending flange has been spun or pressed in to lock or secure the depending paper edge of the neck to the neck 70 ring. Fig. 4, is a vertical section showing an outside paper cap or closure sealing the receptacle mouth and secured by having its depending annular flange spun up under the outer depending portion of the neck 75 ring. Fig. 5, is a vertical section showing a modified formation of the neck ring and to be spun down on the outer edge of a closing cap for securing the same. Fig. 6, is a vertical section showing my receptacle neck or 80 mouth formation with the cap or closure of Fig. 7, applied thereto. Fig. 7, is a detail perspective view of an exterior or cover-all cap particularly adapted for application and locking on receptacle mouths of my formation. Fig. 8, is a vertical section of a modified construction. Fig. 9, is a perspective view of a receptacle mouth or neck portion of my invention of a square or angular 85 outline. Fig. 10, is a vertical section showing a modified formation of neck ring and 90 bottle mouth.

It is the purpose of my invention to provide receptacles made of paper or the like with stiffening neck rings to which the 95 paper material is secured and which is covered by the paper material usually at the top and interior of the receptacle mouth. To this end I provide a metal neck ring or annulus approximately of an inverted U- 100 shape in cross section to form an annular top-wall hollow-body or surface 1. This ring is formed with the short flat annular flange 10, extending inwardly from its lower inner edge, and with the securing flange 11, 105 extending outwardly and then upwardly from its outer lower edge. The body of the paper material receptacle 2, is suitably formed with an elongated neck portion 2^a, which is passed through the open center of 110

the neck ring so as to project the desired distance beyond the same, as indicated by dotted lines Fig. 3. Suitable mechanism is then applied to the extended neck 2^a, and 5 to the portion of the paper material within in the ring to spin or press said neck down onto and over the ring and tightly to the interior and top surfaces of the ring with the outer edge 21, of the paper neck tightly fitting and depending at the outer surface 1, of the ring and within the securing flange 11. A suitable spinning or other tool then 10 tightly presses the flange 11, inwardly to firmly lock and grip the edge 21, of the paper material between the body 1, of the ring and the flange 11, as clearly shown by Fig. 2. While these operations are performed the paper receptacle is firmly held and backed by suitable cores and forms and 15 the neck ring is held and backed by suitable devices.

The paper is spun and pressed over and tightly to the neck ring to form the paper material top edge 20 of the bottle mouth 25 usually by suitable hot dies which cause the paper material to accurately, smoothly and tightly conform to the neck ring and permanently maintain such conformation for the purposes intended.

30 The paper material passes over and is spun or pressed to closely conform to the inner flange 10, to form the internal closing cap or disk receiving shoulder or seat 22, within the bottle mouth to receive an internal closing disk, for instance, such as 3, 35 Figs. 1 and 2. This flat paper material sealing disk 3, is pressed into the receptacle mouth to fit said shoulder and close the receptacle, as will be understood by those skilled in the art. I show the disk provided 40 with a pull tab or handle 30, whereby the same can be lifted from the receptacle mouth. This tab is formed by a small piece of flat wire resting horizontally on the top 45 face of the disk with its outer end 31, passed down through the disk and clenched, while its free end is formed with a perforation 32, to form a grip when the free end of the wire is bent up and grasped to pull out the 50 disk.

In Fig. 4, I show the receptacle sealed by an exterior or cover all cap 4, fitting and conforming to the top edge 20, of the receptacle mouth and having an exterior annular 55 depending flange 40, extending down at the exterior of the bottle mouth and neck ring flange 11, and secured by having its lower edge 41, spun or pressed inwardly around the lower outer edge of the neck ring and 60 upwardly into the recessed under portion of the ring. A permanent or sealed cap is thus provided which cannot be tampered with or removed without destroying the cap or leaving clear evidence of the fact that the cap 65 had been removed and reapplied. Such an

arrangement and provision is of peculiar utility particularly for milk and cream bottles or like receptacles.

In Fig. 5, I show the securing flange 11, of the neck ring formed with an upwardly and outwardly flared cap-securing annular extension 12. I show an exterior cap 5, closing the receptacle mouth and fitting down on and conforming to the top edge thereof and formed with a short annular depending 75 flange or edge 50, within the ring flange extension 12, so that the cap can be secured by spinning or pressing the flange 12 inwardly and down on the cap flange 50, as indicated by dotted lines Fig. 5, or the trough formed 80 by the upwardly and outwardly flaring flange 12, and the cap flange 50, can receive paraffin for the purpose of securing and sealing the paper cap.

In Figs. 6, and 7, I show an exterior or 85 cover all paper cap 6, having an annular depending flange 60, to which are secured several thin flat metal wire strips 61, so that their free ends depend therefrom. This cap is adapted to fit over the bottle mouth as 90 shown in Fig. 6, and be secured by bending the lower or free ends of the metal tabs or strips 61, inwardly under the lower outer edge of the neck ring and then upwardly within the bottom recess of such ring. This 95 arrangement provides what is practically a permanent seal in so far as the cap cannot be readily removed without injuring or destroying the same, the bent ends of the metal tabs being concealed and practically inaccessible.

In Fig. 8, I show a construction wherein the exterior or cover all closing cap 7, is formed with an exterior depending flange 70, permanently secured to the bottle mouth by the neck ring securing flange 11, with the outer edge 21, of the paper material forming the bottle. This permanent cap is shown formed with a depressed center having a small central opening 71, through 105 which the receptacle can be filled and emptied. This opening is adapted to be covered by a small disk 72, and sealed with paraffin 73, or the like deposited in the central depression of the cap.

110 It will be noted that a neck ring of the general type disclosed provides means whereby these various exterior caps can be easily and quickly secured to the receptacle mouths and whereby cap locking or sealing means can be employed and important practical advantages are thereby attained. It 115 will also be noted, that the neck ring provides for the reception of inner closing disks or caps which can be employed with or 120 without exterior or cover all caps.

Attention is particularly directed to the fact that my neck ring is so formed or arranged with respect to the paper material of the vessel as to be completely covered 130

thereby in so far as liability to come in contact with the contents of the receptacle is concerned. This is a feature of importance particularly where milk and other food products are concerned. It will also be noted that the receptacles disclosed provide comparatively smooth paper material walls forming the interior surfaces of the neck and mouth of the receptacle, without objectionable recesses or angular concavities to catch or retain foreign matter or any of the contents of the receptacle.

It will also be noted that the receptacle neck and mouth formation of my invention is applicable to variously shaped receptacles whether round or square and to receive various closures and I do not wish to limit myself to the use of the closures disclosed hereby.

The neck ring greatly stiffens and strengthens the receptacle and imparts the desired rigidity thereto and enables such receptacles to be successfully used in capping machinery for automatic application of closing disks. These neck rings can be employed in small mouth bottles as well as large mouth receptacles imparting the desired rigidity thereto with a minimum use of materials and consequent economy in production, and without detracting from the general appearance of the product or resulting in the production of receptacles of the "freak" type in appearance.

In Fig. 10, I show what is approximately a reversal of the construction shown in the remaining figures of the drawing. In this formation the paper wall 2, is drawn up at the outer side of the metal stiffening ring 1^a, and over the top thereof and then down at the inner side thereof and secured by spinning or pressing the inner upturned flange 1^b, of the ring tightly down on to grip and secure the depending paper flange 2^a. The flange 1^b has an inward annular bulge 2^b, to form the closing-disk-receiving seat in the bottle mouth.

It is evident that various changes, modifications and variations can be resorted to without departing from the spirit and scope of my invention and hence I do not wish to limit myself to the exact disclosures hereof.

Desiring to protect my invention in the broadest manner legally possible, what I claim is:

1. A neck ring for paper material bottles, having an annular upwardly-bulged body portion forming an annular surface around the central opening of the ring to receive the paper material of the bottle to form the inner surface of the bottle neck, and having a top surface to receive said material to form the top edge of the bottle mouth, and at its outer circumferential portion terminating in an outwardly and upwardly extending securing flange.

2. A neck ring for paper material bottles, having an upwardly-bulged paper-material-backing annular body portion at its lower inner edge having a depressed paper-material-backing annular flange in the central opening of the ring, and at its lower outer portion terminating in an outwardly and upwardly extending securing flange. 70

3. A paper material bottle having a neck ring formed with an inner annular sealing-seat-forming flange, said ring covered at its inner and top surfaces by the paper wall of the bottle and at its exterior provided with compressed means tightly gripping the paper thereto and holding the same drawn over said top surface. 75

4. A receptacle having its neck and mouth formed by a paper wall, and a neck ring backing said wall, said ring having a depressed inner annular seat-forming shoulder 85 and an upturned flange forming an annular socket receiving the depending edge of said wall and compressed to grip said edge, said wall extending upwardly beside said ring and drawn over the annular top surface 90 thereof and depending therefrom to said socket.

5. A receptacle having its neck and mouth formed by a paper material wall, and a stiff neck ring backing said wall and having an 95 upturned flange forming an annular socket receiving the depending edge of said wall and compressed to grip said edge, said wall extending upwardly beside said ring and drawn over the annular top surface thereof and depending therefrom to said socket. 100

6. A neck ring for paper material bottles, having top and side surfaces adapted to exteriorly receive the paper material of the bottle to form the edge surrounding the 105 mouth thereof and at its side portion below said surface forming an annular socket to receive the edge portion of the paper material depending from said top surface, said socket being radially compressible to permanently clamp said depending edge portion therein. 110

7. A paper material bottle, having a neck ring covered at its inner and top surfaces by the paper material of the bottle, and radially 115 compressed to tightly grip the paper thereto and drawn thereover.

8. A bottle, having a paper material neck, and a stiffening neck ring therefor, said paper material extending up through said 120 neck and drawn down over the top surface thereof with its edge turned down around the ring and tightly gripped thereto.

9. A bottle, having a paper material neck, and a neck ring having an exterior upturned 125 flange, said paper material extending up through said ring and outwardly over the top surface thereof and downwardly within and gripped by said flange.

10. A bottle having a paper wall neck and 130

4
mouth, and a stiffening ring therefor covered by and over which the paper wall is pressed, the paper wall passing over said ring and depending at the exterior thereof and secured thereto, said ring forming an exterior shoulder for securing a closure over said mouth.

11. A paper material receptacle having a closure seat within its mouth portion, said 10 mouth portion being provided with a flanged stiffening neck ring, the paper material wall

of the receptacle supporting and being compressed and secured to said ring and extending over the top thereof and engaging opposite sides of the ring.

15

In testimony whereof I affix my signature, in presence of two witnesses.

WILBUR L. WRIGHT.
